United States Patent Office

Des. 208,467
Patented Sept. 5, 1967

208,467

BARBER CHAIR

Masaharu Okiyama, 9% Baron Trading Co., Ltd., 48 5-chome, Shuntoku-cho, Fuse, Osaka, Japan

Filed Mar. 15, 1966, Ser. No. 1,468

Term of patent 14 years

(Cl. D15—3)

FIGURE 1 is a front perspective view of a barber chair showing my design;

FIGURE 2 is a side elevational view;

FIGURE 3 is a front elevational view; and

FIGURE 4 is a rear elevational view thereof.

The dominant features of my design reside in those portions shown in full lines on the drawing.

I claim:

The ornamental design for a barber chair, as shown and described.
